UNITED STATES PATENT OFFICE

JULIUS SCHAMBERGER, OF ELIZABETH, NEW JERSEY

APPARATUS FOR SEPARATING OIL FROM WATER

Application filed July 15, 1929. Serial No. 378,260.

This invention relates to the separation of surface layers of material from bodies of liquid, especially the removal of a film of oil from water. The invention will be fully understood from the following description and the accompanying drawings, in which

Fig. 1 is a perspective view of a preferred form of my skimming or separating apparatus, and

Fig. 2 is a vertical section taken on the line A—A in Fig. 1.

Referring to the drawings, a pair of rolls 1, 1a are mounted for rotation on trunnions or shaft extensions 3 and bearing blocks 4 carried by a suitable frame work. This may take the form of sills 2, suitably connected by cross braces 2a. The rolls 1, 1a may be constructed of any suitable material. For best results the outer surfaces 5 thereof should be smooth in texture and free from irregularities. I have found that glass, polished metal, or even wood or paper is suitable for this purpose. I have for instance successfully used paste board rolls coated with oil resistant lacquer.

Suitable mechanism is provided for rotating the rolls, as for instance the intermeshing gears 6, 6a suitably secured to trunnions or shafts 3 and adapted to be rotated in opposite directions by the gear 7, which in turn is mounted on the drive shaft 8 of an electric motor 9 or other source of power. Alternatively, a series of pulleys arranged on the trunnions 3 and carrying cable belts, one of which is connected with an electric motor, may be used for the rotation of the rolls.

Running longitudinally of each roll and closely adjacent the surface thereof I provide scraper knives or doctors 10, 10a adapted to remove the film of oil adhering to the rolls as the latter rotate and transfer it to the troughs 11, 11a which discharge into a common discharge trough or pipe 12 leading to a receiver 13 or other suitable place of disposal.

In operation the rolls 1, 1a are adjusted so as to dip below the surface of the water from which oil is to be separated. This may be accomplished as shown in Fig. 1 by placing the frame 2 over a channel or sluice-way 14 thru which the water flows, the frame 2 being

adjusted so that the rolls 1, 1a are partially submerged.

A baffle 16 extends below the surface of the stream at a point located down stream with respect to the rolls 1, 1a to prevent escape 55 of any traces of oil which may not have been picked up by the rolls. This oil will accumulate on the surface of the water between the baffle 16 and the roll 1a and eventually be picked up by the roll as it rotates. The baffle 16 thus serves to back, or bank, the oil against the roll 1a.

As water carrying on its surface a thin film of oil passes under the rolls 1, 1a which are rotated at a proper rate of speed, the oil 65 film is transferred in whole or in part to the surface of the first roll 1 and is carried around thereon to the knife edge 10 which is set so as to scrape off this film of oil and direct it into the trough 11. Any oil not picked up 70 by the first roll 1 is caught by the second roll 1a as it rotates in the opposite direction and is removed in similar manner by the corresponding knife 10a and trough 11a. The second roll serves to retard the flow of the 75 stream sufficiently to back, or bank, the excess oil between the rolls and permits the first roll to pick up most of the oil. I have, for example, been able with a small skimmer equipped with rolls of approximately four 80 inches diameter and twelve inches in length rotating at a speed of one hundred revolutions per minute to remove from the surface of a stream of water flowing thru the apparatus, oil at the rate of approximately 85 one gallon per minute, the discharge stream of water from opening 15 of the apparatus being entirely free from any trace of oil.

In practice it is obvious that various modifications of my device are possible. It is 90 usually desirable to provide a channel thru which the water carrying a thin film of oil is caused to flow, in which case the walls of the channel may serve as suitable supports for the rolls. Where such an arrangement 95 is used it is desirable also to so arrange the channel that the rolls contact with the surface of the stream throughout its entire breadth. The device will usually be stationary but I contemplate also mounting it 100

for movement with respect to the liquid to be operated upon.

While the invention has been described as applied to the separation of a surface layer of oil from water, it will be understood that other separations can be similarly effected such as the separation of oil from melted paraffin and the like.

Other modifications will suggest themselves to one skilled in the art and while I have described my invention with reference to certain specific details, I wish to claim all modifications and utilizations which come within the spirit and scope of the invention.

15 I claim:—

1. Apparatus for removing floating material from a liquid, which comprises a channel for conveying the liquid, a plurality of spaced rolls each extending transversely across the channel in position to dip into the liquid, means for rotating adjoining rolls in opposite directions with the under-surface of the roll upstream rotating in the direction of travel of the stream, and means for removing and collecting material adhering to the rolls.

2. Apparatus for removing a floating surface layer of material from a liquid, which comprises a channel for conducting the liquid, a roll extending transversely across the channel in position to dip into the liquid, means for rotating the roll with the under-surface of the roll rotating in the direction of travel of the stream, a baffle extending across the channel down stream with respect to the roll in position to dip into the liquid to bank the material passing the roll against the down stream side of the roll, and means for removing and collecting material adhering to the roll.

3. Apparatus for removing floating material from a liquid, which comprises a channel for conducting the liquid, a plurality of spaced rolls each extending transversely across the channel in position to dip into the liquid, means for rotating adjoining rolls in opposite directions with the under-surface of the roll upstream rotating in the direction of travel of the stream, means for removing and collecting material adhering to the rolls, and a baffle extending across the channel downstream with respect to the rolls in position to dip into the liquid to back the material passing the rolls against the down-stream roll.

JULIUS SCHAMBERGER.
